Patented Sept. 23, 1913.

UNITED STATES PATENT OFFICE.

FRANCIS HODGKINSON, OF EDGEWOOD PARK, PENNSYLVANIA, ASSIGNOR TO THE WESTINGHOUSE MACHINE COMPANY, A CORPORATION OF PENNSYLVANIA.

BLADE-SECURING MEANS.

1,073,987.

Specification of Letters Patent. Patented Sept. 23, 1913.

Application filed July 24, 1911. Serial No. 640,250.

To all whom it may concern:

Be it known that I, FRANCIS HODGKINSON, a subject of the King of Great Britain and Ireland, and a resident of Edgewood Park, 5 in the county of Allegheny and State of Pennsylvania, have made a new and useful Invention in Blade-Securing Means, of which the following is a specification.

This invention relates to turbines, and 10 particularly to means for securing the bases or roots of blades to the blade carrying elements.

As is well known, turbine blades are subjected to considerable centrifugal force due 15 to the high rotative speed at which they operate, and in certain types of blades, particularly those usually employed in connection with turbines of the Parsons type, the centrifugal force upon the blades is liable 20 to cause them to become loose and, manifestly, a loose blade in a turbine is a very serious menace to the rest of the blades.

It is one of the objects of my invention to provide a blade-securing means, which will 25 efficiently hold the blades in place and prevent their becoming loose in the actual operation of the turbine.

In carrying out my invention, I preferably construct the blade of a strip of metal, 30 drawn to blade shape, and provide a lip or foot at one end thereof, which may be formed by a die and bulldozer by upsetting the end of the blade. The upset root or foot of the blade is considerably stronger 35 than the bent over portion would be for, manifestly, the upsetting of the blade root forces the molecules of the metal close together, and the roots may be made of any desired thicknesses. The blade root is prefer- 40 ably of less width than the width of the blade, so that it may fit into a groove in the wall of the ordinary turbine blade receiving groove.

The thickness of the root is preferably 45 that of the height of the wall of the supplemental groove, so that the packing pieces may rest firmly upon the floor of the groove and over the root of the blade, so that it will not be necessary to weaken the packing 50 pieces by cutting out portions thereof to receive the blade root. The packing pieces are preferably inserted in undercut portions in the turbine grooves, so that a tendency of a longitudinal bodily movement of the blade

will not displace the packing piece, but will 55 be resisted successfully thereby.

In the drawings forming a part of this specification: Figure 1 is a fragmentary perspective view of a portion of a blade-holding element as, for example, a rotor to 60 which the blades and packing pieces are secured. Fig. 2 is a cross-sectional view through a portion of a row of blades and blade-holding element. Fig. 3 is a detailed perspective view of one of the blades. Fig. 65 4 is a detailed perspective view of one of the packing pieces. Fig. 5 is a top view of a row of blades in place; Fig. 6 is a sectional view on line 6—6 of Fig. 5; and Fig. 7 is a sectional view on the line 7—7 of Fig. 5 70 with some blades in place.

Referring now to the drawings by numerals of reference, 10 designates a blade-holding element provided with a groove 11, in which is a subjacent groove 12 in the floor 75 thereof. The sides of the groove 11 are preferably inclined as at 13 and 14, and to provide undercut portions for the respective packing pieces to be interposed between the respective blades. The blade is best illustrated in Fig. 3. It is shown as comprising the portion 15 having a foot or root 16 at one end thereof, which foot may be formed by being die struck in a bulldozer, so as to upset the metal. In actual practice the upsetting of the end of the blade may extend entirely across the blade, but portions of the root or foot may be cut away so that said foot may be narrower than the width of the 80 blade. 85

In the practical application of the blade it may be found desirable to have the foot of approximately the width of the groove 12, and of approximately the same thickness. The manner of inserting the blade is best 95 shown in Fig. 1, in which the blades are inserted in the groove 11, so that at least one overlapping portion 17 will rest upon the floor of the groove 11 and the foot or lip will be within the groove 12. If desired, the 100 thickness of the root may be slightly less than the depth of the groove 12, so that a space 18 is provided between the bottom of the root and the floor of the groove 12 to allow for contraction and expansion of 105 the root due to difference in temperatures. After the blade is put in place a packing piece 19 may be inserted, which is of greater

width than the width of the blade 15, and which has an inclined portion 20 fitting within the undercut portion of the groove 11 formed by the side wall 13. The opposite side of the packing piece is similarly inclined, as indicated at 21, to be received in the undercut portion 14 of the groove 11. The packing piece 19 may be provided with a shoulder 19^a so that the blade may fit 10 against the curved portion 19^b while that portion beyond the shoulder 19^a may fit into the groove 14. The blades and packing pieces may be inserted into the groove through a cut-away portion 22 in the surface 15 which may subsequently be held in place by the wedges 23 and 24. The packing pieces and blades will be fitted in the grooves alternately, so that each packing piece will rest upon a tongue 16 of its adjacent blade, so 20 that it will be impossible to pull out the blade radially without first removing the packing piece. The packing pieces cannot be removed in a radial direction because their two inclined sides engage in undercut 25 portions of the slot or groove in which they are secured.

If it becomes necessary to remove any blade or a number of blades from the groove 11, the lip 24^a may be cut off or bent back 30 so that the wedge 23 can be removed, then the wedge 24 can be removed and packing pieces and blades may be slid along until they are adjacent the cutaway portion, when they may be readily taken out. New blades

and packing pieces may be then inserted, and 35 after the groove 11 is filled, the wedges 24 and 23 may be inserted, and by bending over the lip 24^a, as indicated in Fig. 7, all of the blades and packing pieces will be held in place.

In accordance with the provisions of the patent statutes, I have described the principle of operation of my invention together with the device which I now consider to represent the best embodiment thereof, but 40 I desire to have it understood that the device shown is only illustrative and that the invention can be carried out in other ways.

Having thus described my invention, what 45 I claim is:

In combination with a grooved blade-holding element having a groove in the floor of the first named groove, a removable blade having a projection at right angles with its body portion and in the second mentioned groove, a packing piece in the first mentioned groove and beneath which the projection on the blade extends, and wedges on the side of the blade and packing piece for holding the packing piece in the groove.

In testimony whereof, I have hereunto 55 subscribed my name this 18th day of July, 1911.

FRANCIS HODGKINSON.
